MODULAR LOW IMPEDANCE FUSE

Frederick J. Kozacka, South Hampton, N. H., assignor to The Chase-Shawmut Company, Newburyport, Mass.

Application July 22, 1955, Serial No. 523,832

3 Claims. (Cl. 200—135)

of the invention and advantages thereof will more clearly appear from the ensuing particular description thereof, as illustrated in the drawing wherein

Fig. 1 is a section of a sub-assembly used to make fuses embodying the invention;

Fig. 2 is a side elevation of the structure shown in Fig. 1;

Fig. 3 is substantially a longitudinal section of a fuse embodying the invention;

Fig. 4 is substantially a longitudinal section of another fuse embodying the invention;

Fig. 5 is substantially a longitudinal section of the fuse shown in Fig. 4 taken at 90 degrees to the plane of Fig. 4;

Fig. 6 is substantially a longitudinal section of a fuse having a relatively high voltage rating embodying the invention;

Fig. 7 is a front elevation of a piece of material used for manufacturing the sub-assembly shown in Figs. 1 and 2, and

Fig. 8 is a cross-section along 8—8 of Fig. 7 showing the piece of material in another stage of the manufacturing process.

All figures are drawn on very much enlarged scales, the scale of Figs. 1 and 2 being larger than that of the other figures.

Referring now to Figs. 1 and 2, reference character 1 has been applied to generally indicate a laminated disc or block. This disc or block comprises outer laminations 2 of a metal having a high conductivity, e. g. copper, and inner lamination 3 of a relatively heat resistant insulating material. Laminations 2, 3, 2 are bonded together to form a self-sustained structural unit.

Passage 4 having a relatively small diameter is provided transversely across outer laminations 2 and inner lamination 3. Wire type fuse link 5 preferably of a high fusing point metal such as silver or copper is threaded through passage 4 and conductively connected at each end thereof, e. g. by means of joints 6 of soft solder, to one of the outer laminations 2. Wire 5 is preferably tin plated for reasons which will hereinafter be set forth in detail.

Assuming that the current normally carried by wire 5 is exceeded at a given time. If the rate of rise of current from normal is very low, there will be a tendency for the excess heat generated to be absorbed and dissipated by the laminations 2. If the rate of rise of the current from normal is not very low, there will be a tendency for thermal destruction of wire 5, as a result of which an arc is kindled in passage 4 in the space thereof situated within insulating lamination 3. This results in a pressure build-up in passage 4 followed by a sudden arc-extinguishing blast of gas out of the ends of passage 4. This blast may be slightly delayed until the ends of the passage 4 normally closed by solder joints 6 are opened by virtue of the heat generated within passage 4, softening of the masses 6 of solder and the pressure exerted upon masses 6 from within passage 4. Considerable blast velocities are being reached as the gases, i. e. the hot products of arcing, escape out of passage 4 through the holes provided in laminations 2. Lamination 3 consists preferably of an organic insulating material evolving relatively large amounts of arc-quenching and arc-diluting gases when subjected to the heat of the arc, which may be in the order of several thousand degrees centigrade.

The structures shown in Figs. 3 to 5 comprise sub-assemblies identical to that illustrated in Figs. 1 and 2.

According to Fig. 3 such a sub-assembly 1 is enclosed in the tubular casing 7 of insulating material closed on both ends by caps 8 of sheet metal mounted thereon.

The foregoing and other general and special objects

The outer diameter of sub-assembly 1 is substantially the same as the inner diameter of casing 7 so that sub-assembly 1 fits loosely into casing 7. Sub-assembly 1 is held in position by a pair of helical springs 9 of which each rests with one end thereof against one of the outer laminations 2 and with the other end thereof against one of the terminal caps 8. Springs 9 have a relatively low resistance, i. e. the resistance of one unit length of springs 8 is very small compared to the resistance of one unit length of link wire 5. If desired, springs 9 may be silver plated to decrease their ohmic resistance. Caps 8 may be permanently secured to casing 7 by crimping of the axially inner ends thereof.

The fuse structure shown in Figs. 4 and 5 comprises a casing 7' of insulating material supporting a terminal cap or ferrule 8' on each end thereof. Sub-assembly 1 is arranged substantially midway between the ends of insulating casing 7'. The solder joints 6 of sub-assembly 1 which connect the fuse wire 5 to metal laminations 2 are also used for conductively connecting a pair of metal ribbons 10 to the metal laminations 2. Ribbons 10 consist preferably of copper and are bent at the axially outer ends thereof around the edges of of casing 7' as can clearly be seen in Fig. 5. Metal ribbons 10 are preferably tinned, e. g. by tin plating. This enables to conveniently establish a blind solder joint at the points 10' between the inner surfaces of caps 8' and ribbons 10 by applying heat to the caps 8'. It will be observed that the space within casing 7' does not contain any pulverulent arc-quenching filler. Quenching of the arc formed upon fusion of link 5 is achieved by blasts of gas evolved from insulating lamination 3 under the heat of the arc and escaping through the outer ends of passage 4 upon being opened by the action of heat and pressure.

Referring now to Fig. 6, the fuse shown therein comprises a casing 7" of insulating material closed by crimped caps 8" and housing a plurality of series connected sub-assemblies 1, i. e. three such sub-assemblies. These sub-assemblies are spaced from each other and conductively interconnected by means of springs 9' and 9". Springs 9' are arranged between the sub-assemblies 1, and springs 9" are arranged between the axially outer sub-assemblies 1 and the caps 8".

Figs. 7 and 8 show a sheet 11 of a material comprising an inner lamination of insulating material sandwiched between two outer sheets of copper. Circular holes 11a in sheet 11 are formed by a stamping operation and the discs 12 resulting from that operation are subsequently used to make up such units as shown in Figs. 1 and 2. Fig. 8 shows a number of discs 12 upon removal thereof from the parent laminated sheet. Each disc 12 is provided with a central fuse-link-receiving bore which bores may be drilled into sheet 11 before the stampings 12 are being made. It will be apparent from the foregoing that the cylindrical insulating edge faces of stampings 1 are flush with the metallic edge faces thereof.

The preferred material for making the discs 12 is of the type used in the electronic industry for making so-called printed circuits. Such circuits are made from copper-clad sheets comprising thin layers of copper laminated to both sides of a plastic sheet of desired grade and thickness. Not any material applicable for printed circuits can be used for making discs 12 since it may be necessary for discs 12 to withstand higher temperatures than normally necessary for printed circuits, or in the manufacture of printed circuits. A tin coating on the fusible wire 5 permits to associate the wire with plastic materials which have a relatively limited heat withstanding ability. If it is desired to further reduce the operating temperature of the fusible wire 5, the latter may be made of indium coated silver. This results in a drastic reduction of the operating temperature as more fully shown in United States Patent 2,703,352 to Frederick J. Kozacka, Fuse and Fuse Link of the Time Lag Type, March 1, 1955. If the mass of tin, indium, or

indium alloy, or other low fusing point link-destroying alloy-forming metal coated on wire 5 is relatively small, the link-destroying alloy-forming action of the overlay will occur very rapidly, i. e. not involve any time delay.

Glass base laminates are particularly suitable for the purpose in hand since glass or quartz has a very high heat absorbing capacity. Thus discs made of glass base laminates are able to absorb considerable amounts of arc energy, in addition to the good dimensional stability, and other desirable properties, which they offer. Various types of synthetic resins are suitable to form the inner layer 3 of the sandwich which is laminated between the outer metal layers 2 such as, for instance, silicone resins, melamine resins, or epoxy type resins. The resins must be selected with due consideration to the object of evolving arc-quenching gases when subjected to the heat of the arc which gases should not contain anything as, for instance, carbon, which would tend to make circuit interruption more onerous. Fiber glass silicon is best suited for relatively high operating temperatures.

The mass of the coating of link-destroying, alloy-forming low fusing point metal, e. g. tin or indium, with which link wire 5 is coated should be compared to the mass of the link wire 5. The tin or indium coating may be less than $\frac{1}{1000}$ " thick. If the mass of link-destroying alloy-forming low fusing point metal were only slightly less, of the same order, or larger than the mass of the link wire 5, a time delay or time lag effect would result rather than an acceleration of the interrupting process. If the layer of link-destroying, alloy-forming low fusing point metal is sufficiently thin, the time involved in destruction or disintegration of link wire 5 mainly by dissolution thereof in the fused alloy-forming overlay is less than the time required to thermally destroy link wire 5 without auxiliary link-destroying alloy-forming action merely by heating it to the fusing point of the base metal thereof.

It will be understood that I have illustrated and described several embodiments of my invention and that various alterations may be made in the details thereof without departing from the invention as defined in the appended claims.

I claim:

1. An instrument type fuse comprising a stamping formed from metal-clad laminated plastic sheet material of the kind used for printed circuits comprising a pair of layers of sheet metal laminated on both sides of a sheet of a synthetic resin evolving gas when subjected to the heat of an electric arc, the insulating edge face of said stamping being flush with the metallic edge faces thereof, and a short length of fuse wire threaded through a bore projecting transversely across said stamping and conductively connected to the metallic surfaces thereof.

2. An instrument type fuse comprising a stamping formed from metal-clad laminated plastic sheet material comprising a pair of outer laminations of metal and an inner lamination of an insulating material evolving gas when subjected to the heat of an electric arc and capable of withstanding but a relatively low ceiling temperature, the insulating edge face of said stamping being flush with the metallic edge faces thereof, a short length of a fuse wire having a relatively high fusing point threaded through a bore projecting transversely across said stamping and conductively connected to the metallic parts thereof, and an overlay of a relatively low fusing point metal on said fuse wire causing disintegration thereof at temperatures below said relatively high fusing point.

3. An instrument type fuse comprising a stamping formed from a metal-clad laminated plastic sheet material comprising a pair of outer laminations of metal and an inner lamination of an organic insulating material, the insulating edge face of said stamping being flush with the metallic edge faces thereof; a relatively short length of a fuse wire having a relatively high fusing point threaded through a bore projecting trans-

versely across said stamping, the ends of said wire being brought out of said bore, bent upon the outer surfaces of said stamping and soldered thereon; and an overlay of a relatively low fusing point metal on said wire causing disintegration thereof at temperatures below said 5 relatively high fusing point.
